(57) **CLAIM**

The ornamental design for fence panel, as shown and described.

DESCRIPTION

FIG. 1 is a top plan view of a fence panel showing my new design;

FIG. 2 is a bottom plan view thereof;

FIG. 3 is a front elevational view of the fence panel on a reduced scale;

FIG. 4 is a front elevational view of a section of the fence panel on a reduced scale;

FIG. 5 is a rear elevational view of the fence panel on a reduced scale;

FIG. 6 is a rear elevational view of a section of the fence panel on an enlarged scale;

FIG. 7 is a right side elevational view of the fence panel on a reduced scale;

FIG. 8 is a right side perspective view of a section of the fence panel on an enlarged scale;

FIG. 9 is a left side elevational view of the fence panel on a reduced scale;

FIG. 10 is a left side perspective view of a section of the fence panel on an enlarged scale; and,

FIG. 11 is a perspective view of a fence panel on a reduced scale in condition of use with a plurality of like fence panels with fence posts and secured by nails.

The broken lines are for environmental purposes only and form no part of the claimed design.
